UNITED STATES PATENT OFFICE

2,667,753

AUTOMATIC DEFROST CONTROL

Charles S. Grimshaw, Erie, Pa., assignor to General Electric Company, a corporation of New York

Application December 19, 1951, Serial No. 262,446

12 Claims. (Cl. 62—2)

1

My invention relates to defrosting apparatus and more particularly to controls for automatically effecting defrosting of refrigerator evaporators.

In many household refrigerators, the evaporator for cooling the food storage compartment is exposed to the air in this compartment. Since the evaporator is at a colder temperature than the air and below the freezing point of water, moisture condenses on the evaporator and forms as frost. Ultimately, in order to maintain the desired operating efficiency of the evaporator, it is necessary to remove this insulating layer of frost. Since the removal of this frost manually is a somewhat distasteful and time-consuming task, it is desirable to provide some automatic means for effecting the defrosting of the evaporator at intervals.

Accordingly, it is an object of my invention to provide an improved control for automatically effecting defrosting of an evaporator.

It is another object of my invention to provide an improved control for automatically introducing an additional opposing force for defrosting.

It is a further object of my invention to provide an improved arrangement for starting refrigeration at the expiration of the defrosting period.

It is still another object of my invention to provide a control including an improved arrangement for obtaining a defrost temperature setting which is independent of changes in the normal temperature setting.

Further objects and advantages of my invention will become apparent as the following description proceeds and the features of novelty which characterize my invention will be pointed out with particularity in the claims annexed to and forming part of this specification.

In carrying out the objects of my invention, an interfering member is provided for acting as a stop, opposing movement of an operating arm of the control to the refrigeration-starting position when defrosting is to be accomplished. The position of this member is controlled by a rotatable cam which is periodically advanced during normal operation of the control. The member prevents movement of the operating arm to the refrigeration-starting position until a greater than normal expansion of the temperature-responsive device of the control has occurred, that is until the temperature of the evaporator has reached a predetermined abnormally high temperature. This additional ex-

2

pansion of the temperature-responsive element is opposed by a defrost spring. When the abnormally high temperature has been reached, a trip arm, movable by the temperature-responsive element, effects a shifting of the interfering member to remove the opposition of this member to movement of the operating arm of the control to the refrigeration-starting position. In one form of my invention a toggle member is employed as the interfering member and the trip arm is arranged to effect a breaking of the toggle member to terminate the defrosting period.

For a better understanding of my invention reference may be had to the accompanying drawing in which Fig. 1 is a view, partly in section, of a control device incorporating an embodiment of my invention during normal operation of the refrigerating system; Fig. 2 is a view on a slightly reduced scale of the apparatus of Fig. 1 in the defrosting position; Fig. 3 is a view of a portion of the control of the end of the defrosting period; Fig. 4 is another view of the control shortly after the termination of the defrosting period; and Fig. 5 is a detail view of a modification of the invention.

Referring to the drawing, the control is shown as applied to controlling the position of a valve 1 for governing flow of refrigerant from a conduit 2 to a conduit 3. Refrigerant is supplied through conduit 3 to an evaporator or other cooling unit (not shown). The valve 1 includes a valve plunger 4 adapted to engage a valve seat 5. A magnet 6 is secured to the upper end of the plunger, and the position of this magnet and of the plunger is controlled by a movable yoke 7 acting on the magnet. While in the specific illustration, the control has been shown acting to control the position of the valve for governing the flow of refrigerant to an evaporator or other cooling unit, it will be apparent as the following description proceeds that this control can equally well be employed for opening and closing contacts to stop and start a refrigerating unit in the conventional manner employed in such controls.

The valve-controlling yoke 7 is mounted on one end of a two-part operating arm 8. This operating arm 8 includes a first part or element 9 and a second part or element 10. These parts are related by a hairpin spring 11, knife edges 12 and 13 of these parts of the arm 8 engaging opposite sides of the hairpin spring 11. This construction of the operating arm 8 including the hairpin spring 11 is employed to secure snap action operation in a manner well known in the art. The first part 9 of the operating arm 8 is

pivotedly mounted between upstanding projections 14 secured to the housing 15 of the control. The second part 10 of the operating arm 8 is supported from a depending bracket 16 which is secured by a rivet 17 or other suitable fastening device to a wall of the housing 15. The part 10 is connected to the bracket 16 by a flat resilient strip 18 which affords the necessary movement of the part 10 of the operating arm 8. The resilient strip 18 is secured by rivets 19 or other suitable fastening devices to the bracket 16 and to the part 10 of the operating arm 8.

In order to effect movement of the operating arm 8 between one position for opening the valve to start refrigeration and a second position for closing the valve to stop refrigeration, a temperature-responsive element or bellows 20 is mounted on the housing 15. The bellows 20 is connected by a tube 21 to a thermostatic bulb (not shown) positioned to be responsive to the temperature of the evaporator. The operating arm 8 is biased by a spring 22 which engages the part 9 of the operating arm 8. A cap 23 is provided for the upper end of the spring 22 and an adjusting screw 24 threaded into the wall of the housing 15 engages the cap 23 for varying the biasing force exerted by the spring 22. The part 9 of the operating arm 8 includes an upwardly extending boss 25 for assisting in positioning the lower end of the spring 22.

Under normal operating conditions, that is during normal cycling of the refrigerating system, the movement of the operating arm 8 and hence the position of the valve 1, is controlled by the expansion and contraction of the bellows 20 under the biasing force of the opposing spring 22. For example, in the position of the apparatus shown in Fig. 1, the yoke 7 is in its lower position, attracting the magnet 6 upwardly and lifting the valve plunger 4 to supply refrigerant to the evaporator. As the temperature of the evaporator is lowered, the bellows 20 contracts and the part 9 of the operating arm 8 is moved downwardly by the spring 22. This effects a downward movement of the knife edge 12, eventually bringing this knife edge 12 below a line extending through the knife edge 13 and the pivot point of the part 10 of the arm 8. Then, through the action of the hairpin spring 11, a snap action upward movement of the part 10 of the operating arm 8 is effected. This shifts the yoke 7 to the upper position corresponding to that shown in Fig. 2, attracting the magnet 6 downwardly to close the valve and discontinue supply of refrigerant. Conversely as the evaporator then warms to a predetermined maximum temperature, the bellows 20 expands and acts through the interposed trip arm 26 to raise the part 9 of the operating arm 8, effecting a snap action movement of the yoke 7 to the position shown in Fig. 1, thereby again opening the valve 1.

During normal operation, the control cycles between the refrigeration-starting and refrigeration-stopping positions in the manner described above. After a number of such cycles over a period of time, frost builds up on the evaporator to a sufficient extent to have an adverse effect on the efficiency of the evaporator in effecting cooling of the air in which it is disposed. In accordance with my invention, after a predetermined number of such normal cycles of the control, the control is automatically positioned for effecting a temporary abnormally high temperature of the evaporator sufficient to insure melting of all frost from the evaporator. In order to effect

such defrosting, a toggle member or stop 27 is provided for opposing downward movement of the part 10 of the operating arm 8 until the evaporator has reached the predetermined abnormally high temperature. The position of the toggle member or interfering member 27 is controlled by a rotatable disk or cam 28. This cam 28 is periodically advanced by the cycling of the control during normal operation. Specifically, a depending pawl 29, which may be mounted on the part 9 of the operating arm 8 by a rivet or other suitable fastening device 30 or which may be formed integrally with part 9 is arranged to engage a ratchet wheel or ratchet 31. The ratchet wheel 31 is connected through gears 32 and 33 to rotate the cam 28. The ratchet wheel 31, the gears 32 and 33 and the cam 28 are all rotatably mounted on supports or brackets, one of which is shown at 34, extending upwardly from the base of the housing 15. It can be seen that each time the part 9 of the operating arm 8 is moved upwardly at the start of a refrigerating cycle, the pawl 29, engaging the teeth of the ratchet wheel 31, moves the ratchet wheel in a clockwise direction. The teeth on the ratchet wheel are chosen so that the normal upward movement of the pawl 29 advances the ratchet wheel by the amount of one tooth. Reverse rotation of the ratchet wheel 31 during the downward movement of the part 9 of the operating arm 8 at the end of the refrigerating portion of the operating cycle is prevented by a fixed resilient strip or pawl 35 which is secured to or formed integral with one of the supports 34 and which engages the teeth of the ratchet wheel 31.

The toggle member 27 includes two pivoted elements 36 and 37. These pivoted elements 36 and 37 are pivotally connected at the knuckle 38 of the toggle member. The pivoted element 36 of the toggle member is of channel shape and includes an upper knife edge 39 adapted to engage a depending flange 40 of the part 10 of the operating arm 8 under defrosting conditions. The lower end of the base of the channel section of the pivoted element 36 is bent out to form a tongue 41 adapted to engage the periphery or surface 42 of the rotatable disk or cam 28. The lower pivoted element 37 of the toggle member 27 is formed from an elongated rod, bent to provide a loop portion 43 received within a slot 44 in a support 45 at the base of the housing 15. The loop portion 43 is retained within the slot 44 by a closure element 46 which blocks the opening of the slot 44. The pivoted element 37 further includes a rearwardly extending horizontal portion adapted to pass through openings in the channel-shaped upper pivoted element 36 at the knuckle 38. The element 37 further includes a forwardly extending end portion 47 which is adapted to engage the pivoted element 36 to limit the counterclockwise rotation of this pivoted element 36. The toggle member 27 and specifically the tongue 41 of the upper pivoted element 36 thereof is biased into engagement with the periphery 42 of the cam 28 by a spring 48. One end of the spring 48 is secured to an upwardly extending ear 49 mounted on the base of the housing 15 and the other end of the spring is secured in an opening 50 in the pivoted element 36 of the toggle member 27.

During normal operation of the refrigerating system, the toggle member 27 occupies the position shown in Fig. 1, being held in this position against the bias of the spring 48 by the engagement of the tongue 41 with the periphery 42 of

the cam 28. The cam 28 includes a recess 51 in its periphery or surface 42. As ratchet wheel 31 is periodically advanced during the normal cycling of the control, the cam 28 is rotated in a counterclockwise direction, as indicated by the arrow, and the recess 51 is progressively moved toward alignment with the tongue 41 of the toggle member 27. When the recess 51 reaches alignment with the tongue 41, the tongue 41 passes into the recess 51 under the influence of the biasing spring 48, and the toggle member 27 is then moved into the position shown in Fig. 2. In the position shown in Fig. 2, the knife edge 39 is positioned to engage the lower tip of the flange 40 and thereby to oppose downward movement of the part 10 of the operating arm 8 to the lower position in which the valve 1 is opened and refrigeration is started. The construction of the toggle member 27 is such that in the position shown in Fig. 2, the knuckle 38 thereof is to the right of a line extending between the knife edge 39 and the loop portion 43, and hence the toggle member is disposed overcenter toward the right, this overcenter positioning being assisted by the spring 48. Normal operation of the refrigerating system is discontinued by the shifting of the toggle member 27 to the position shown in Fig. 2 since the downward movement of the part 10 of the operating arm 8 to the refrigeration-starting position is positively prevented. In order to remove this blocking force of the toggle member 27 when the temperature of the evaporator has reached a predetermined abnormally high value which insures completion of defrosting thereof, the trip arm 26 is provided for engaging a leg 52 of the lower pivoted element 37 of the toggle member 27. The trip arm 26 is pivotally mounted in engagement with the part 9 of the operating arm 8, this engagement being effected at a knife edge 53 at the end of the trip arm 26. The bellows 20 is arranged in engagement with a recessed portion 54 of the trip arm 26, and the expansive force of the bellows resulting from the increase in temperature of the evaporator is exerted upwardly against the trip arm 26. The upward movement of the bellows under defrosting conditions is opposed by a defrosting spring 55. One end of the spring 55 is arranged in engagement with the part 9 of the operating arm 8 and the other end engages a cup 56. The opposing force exerted by the spring 55 is adjusted by a screw 57 which engages the cup 56 and is in threaded engagement with an opening in the trip arm 26.

The upward movement of the part 9 of the operating arm 8, that is, the movement of the operating arm in the refrigeration-starting position is limited by a stop 58 bent from the bracket 16. Movement of the trip arm 26 away from the part 9 of the operating arm 8 is limited by a stop 58a. As the temperature of the evaporator rises above the normal maximum temperature toward the abnormally high maximum defrosting temperature, further movement of the part 9 of the operating arm 8 and further compression of the spring 22 are prevented by the stop 58. Accordingly, the increased expansion of the bellows moves the trip arm 26 away from the stop 58a and upwardly against only the bias of the spring 55. It will be noted, therefore, that the abnormally high maximum defrosting temperature setting, as established by the adjusting screw 51, is independent of the adjustment of the spring 22 which determines the normal maximum and minimum temperatures.

The broad idea of a control including two arms, a normal biasing spring engaging one arm and a defrost spring between the arms, and including a stop engaging the one for rendering the normal biasing spring ineffective so as to make the defrost temperature independent of the normal temperature setting is not part of the present invention but is described and claimed in my co-pending application, Serial No. 203,166, filed December 28, 1950, now Patent No. 2,627,561, issued February 3, 1953, and assigned to the same assignee as the present invention.

Ultimately, the trip arm 26 reaches a position wherein the end thereof engages the leg 52 of the lower pivoted element 37 of the toggle member 27. Further upward movement of the trip arm 26 then pivots this lower element 37 in a counterclockwise direction, moving the knuckle 38 overcenter to the left with respect to the knife edge 39 and the loop portion 43, as shown in Fig. 3, breaking the toggle member 27. This removes the blocking effect of the toggle member 27 to the downward movement of part 10 of the operating arm 8. The part 10 of the operating arm 8 then snaps downwardly overcenter to open the valve 1 and start refrigeration, terminating the defrost period. The aforementioned breaking of the toggle member 27 effects movement of the tongue 41 out of the recess 51 of the cam 28, because part of the energy stored in spring 11 is transferred to toggle member 27 and causes it to move rapidly to the left, thereby freeing itself from flange 40. Since the cam 28 is not advanced further until there is an upward snap action movement of the part 10 of the operating arm 8 at the start of the refrigerating portion of the next normal operating cycle, the recess 51 still remains in substantial alignment with the tongue 41. Accordingly, in the absence of special provision, the tongue 41 could re-enter the recess 51 when the bellows 20 had contracted sufficiently to move the trip arm 26 downwardly out of engagement with the leg 52 of the lower pivoted element 37. In order to prevent such undesired re-entry of the tongue 41 into the recess 51, a resilient element 59 is provided. The resilient element 59 is mounted on the shaft of the cam 28 and includes a portion 60 disposed in the general region of the periphery of the cam 28 immediately adjacent the recess 51. As the cam 28 is advanced toward the defrosting position shown in Fig. 2, the resilient element 59 is engaged by the tongue 41 at the portion 61 which projects slightly beyond the periphery 42 of the cam 28, and the resilient element 59 is forced in a clockwise direction beyond the edge 62 of the recess 51, affording space for entry of the tongue 41 into the recess 51 to initiate the defrosting period. When the tongue 41 is withdrawn from the recess 51 at the termination of the defrosting period, the resilient member 59 moves counterclockwise to resume its original position, as shown in Fig. 4, blocking re-entry of the tongue 41 into the recess 51.

In the modified form shown in Fig. 5 a single pivoted interfering member 63 is substituted for the toggle member 27 for blocking the movement of the part 10 of the operating arm 8. The member 63 is pivoted at 64 and includes a leg 65 corresponding to the leg 52 of the form previously described. The member 63 further includes a tongue 66 corresponding to the tongue 41 in the form of invention shown in Figs. 1 to 4 inclusive. The member 63 is biased against the cam or disk 28 by a spring 48. In order to reduce the friction

and minimize variations in the operation of the device, a roller 67 is mounted on a pin 68 at the upper end of the member 63. The roller 67 is adapted to engage the depending flange 40 on the operating arm 8. The trip arm 26 is arranged to engage the leg 65 for swinging the member 63 counterclockwise out of its blocking position after a predetermined abnormally high temperature has been reached during the defrosting period.

The operation of the device shown in Fig. 5 is essentially the same as that of the form of control previously described. When the recess 51 is moved into alignment with the tongue 66, the pivoted member 63 swings into the position shown in Fig. 5, the position of the member 63 being established by the biasing spring 48 and the engagement of the end of the tongue 66 with the bottom of the recess 51. In this position the member 63 is arranged to engage the lower end of the flange 40 and to block downward movement of the part 10 of the operating arm 8 to the refrigeration-starting position. Under these conditions, a further expansion of the bellows 20 is required to move the trip arm upwardly against the bias of the spring 55, as in the form illustrated in Fig. 1. Ultimately, the expansion of the bellows moves the end of the trip arm 26 into engagement with the leg 65 of the pivoted member 63, swinging this member counterclockwise and moving the roller 67 from beneath the lower end of the flange 40. This permits the part 10 of the operating arm 8 to move downwardly, terminating the defrost period and initiating refrigeration. In the event that a greater error resulting from variations in friction can be tolerated, the roller 67 can be omitted, the solid upper end of the pivoted member 63 then directly engaging the flange 40.

While I have shown and described specific embodiments of my invention, I do not desire my invention to be limited to the particular constructions shown and described, and I intend, by the appended claims, to cover all modifications within the spirit and scope of my invention.

What I claim as new and desire to secure by Letters Patent of the United States is:

1. A refrigerator control comprising a pivoted operating arm movable between two positions for starting and stopping refrigeration at predetermined maximum and minimum temperatures, a temperature-responsive element for effecting movement of said arm, a biasing spring engaging said arm for opposing said element, a pivoted interfering member movable between a first position wherein said member acts as a stop for said arm and a second position wherein said member does not obstruct movement of said arm, said member including a roller at one end thereof for engaging said arm, a cam engaging said member for affording movement of said member between said first and second positions, and means actuated at a predetermined abnormally high maximum temperature for shifting said member from said first position to said second position to terminate opposition by said member to movement of said arm.

2. A refrigerator control comprising a pivoted operating arm movable between two positions for starting and stopping refrigeration at predetermined maximum and minimum temperatures, a temperature-responsive element for effecting movement of said arm, a biasing spring engaging said arm for opposing said element, a toggle member movable between a first position wherein said toggle member acts as a stop for

said arm and a second position wherein said toggle member does not obstruct movement of said arm, a cam engaging said toggle member for affording movement of said toggle member between said first and second positions, and a pivoted trip arm for engaging said toggle member at a predetermined abnormally high maximum temperature when said toggle member is in said first position for breaking said toggle member to terminate opposition by said toggle member to movement of said arm.

3. A refrigerator control comprising a pivoted operating arm movable between two positions for starting and stopping refrigeration at predetermined maximum and minimum temperatures, a temperature-responsive element for effecting movement of said arm, a biasing spring engaging said arm for opposing said element, a toggle member movable between a first position wherein said toggle member acts as a stop for said arm and a second position wherein said toggle member does not obstruct movement of said arm, a cam, a spring for biasing said toggle member overcenter in one direction against said cam, said cam affording movement of said toggle member between said first and second positions, and means actuated at a predetermined abnormally high maximum temperature when said toggle member is in said first position for shifting said toggle member overcenter in the opposite direction to terminate opposition by said toggle member to movement of said arm.

4. A refrigerator control comprising a pivoted operating arm movable between two positions for starting and stopping refrigeration at predetermined maximum and minimum temperatures, a temperature-responsive element for effecting movement of said arm, a biasing spring engaging said arm for opposing said element, a toggle member movable between a first position wherein said toggle member acts as a stop for said arm and a second position wherein said toggle member does not obstruct movement of said arm, a cam, a spring for biasing said toggle member overcenter in one direction against said cam, said cam affording movement of said toggle member between said first and second positions, and means actuated at a predetermined abnormally high maximum temperature when said toggle member is in said first position for shifting said toggle member overcenter in the opposite direction to terminate opposition by said toggle member to movement of said arm.

5. A refrigerator control comprising a pivoted operating arm movable between two positions for starting and stopping refrigeration at predetermined maximum and minimum temperatures, a temperature-responsive element for effecting movement of said arm, a biasing spring engaging said arm for opposing said element, a toggle member movable between a first position wherein said toggle member acts as a stop for said arm and a second position wherein said toggle member does not obstruct movement of said arm, a rotatable cam including a recess therein, said toggle member including a tongue for engaging said cam, said cam being rotatable to position said recess in alignment with said tongue to afford movement of said toggle member into said first position, a resilient element adjacent said recess to block entry of said tongue thereinto, said tongue engaging said resilient element at one point in the rotation of said cam to move said resilient element for at least partially re-

moving blockage of said recess, and means actuated at a predetermined abnormally high maximum temperature when said toggle member is in said first position for breaking said toggle member to terminate opposition by said toggle member to movement of said arm.

6. A refrigerator control comprising a pivoted operating arm movable between two positions for starting and stopping refrigeration at predetermined maximum and minimum temperatures, a temperature-responsive element for effecting movement of said arm, a biasing spring engaging said arm for opposing said element, a pivoted member movable between a first position wherein said pivoted member acts as a stop for said arm and a second position wherein said pivoted member does not obstruct movement of said arm, a rotatable cam including a recess therein, said pivoted member including a tongue for engaging said cam, a spring for biasing said tongue against said cam, said cam being rotatable to position said recess in alignment with said tongue to afford movement of said pivoted member into said first position, a resilient element adjacent said recess to block entry of said tongue thereto, said tongue engaging said resilient element at one point in the rotation of said cam to move said resilient element for at least partially removing blockage of said recess, and means actuated at a predetermined abnormally high maximum temperature for moving said pivoted member from said first position to said second position to terminate opposition by said pivoted member to movement of said arm.

7. A refrigerator control comprising a pivoted operating arm movable between two positions for starting and stopping refrigeration at predetermined maximum and minimum temperatures, a temperature-responsive element for effecting movement of said arm, a biasing spring engaging said arm for opposing said element, a toggle member movable between a first position wherein said toggle member acts as a stop for said arm and a second position wherein said toggle member does not obstruct movement of said arm, a rotatable disk engaging said toggle member for effecting movement of said toggle member between said first and second positions, said disk including a recess in the periphery thereof, said toggle member including a tongue engaging the periphery of said disk, a ratchet, a pawl mounted on said operating arm and engaging said ratchet for advancing said ratchet each time said operating arm is moved between stopping and starting positions, gear means between said ratchet and said disk for effecting rotation of said disk upon movement of said ratchet, means dependent upon a predetermined number of actuations of said ratchet for positioning said recess in alignment with said tongue to afford movement of said toggle member to said first position, and a pivoted trip arm for engaging said toggle member at a predetermined abnormally high maximum temperature when said toggle member is in said first position for breaking said toggle member to terminate opposition by said toggle member to movement of said arm.

8. A refrigerator control comprising a pivoted two-part operating arm including a first part and a second part, an overcenter spring between said parts for effecting relative snap action movement of said parts, a temperature-responsive element for effecting movement of said first part of said arm, a biasing spring engaging said first part of said arm for opposing said temperature-

responsive element, a stop for engaging said second part of said arm for opposing movement of said operating arm to its refrigeration-starting position, said stop comprising a toggle member movable between a first position wherein said toggle member blocks movement of said operating arm to its refrigerant-starting position and a second position wherein said toggle member does not obstruct movement of said operating arm, a cam engaging said toggle member for affording movement of said toggle member between said first and second positions, and means actuated at a predetermined abnormally high maximum temperature when said toggle member is in said first position for breaking said toggle member to terminate opposition by said toggle member to movement of said arm.

9. A refrigerator control comprising a pivoted two-part operating arm including a first part and a second part, an overcenter spring between said parts for effecting relative snap action movement of said parts, a temperature-responsive element for effecting movement of said first part of said arm, a biasing spring engaging said first part of said arm for opposing said temperature-responsive element, a stop for engaging said second part of said arm for opposing movement of said operating arm to its refrigeration-starting position, said stop comprising a toggle member movable between a first position wherein said toggle member blocks movement of said operating arm to its refrigerant-starting position and a second position wherein said toggle member does not obstruct movement of said operating arm, said toggle member including two pivoted elements, a cam, a spring for biasing one of said pivoted elements against said cam and for biasing said toggle member overcenter in one direction, said cam affording movement of said toggle member between said first position and second position, and a pivoted trip arm for engaging the other of said pivoted elements of said toggle member to shift said toggle member overcenter in the opposite direction for terminating opposition by said toggle member to movement of said arm.

10. A refrigerator control comprising a pivoted two-part operating arm including a first part and a second part, an overcenter spring between said parts for effecting relative snap action movement of said parts, a temperature-responsive element for effecting movement of said first part of said arm, a biasing spring engaging said first part of said arm for opposing said temperature-responsive element, a stop for engaging said second part of said arm for opposing movement of said operating arm to its refrigeration-starting position, said stop comprising a toggle member movable between a first position wherein said toggle member blocks movement of said operating arm to its refrigeration-starting position and a second position wherein said toggle member does not obstruct movement of said operating arm, said toggle member including two pivoted elements, a rotatable disk, one of said pivoted elements of said toggle member including a tongue adapted to engage the periphery of said disk, a spring for biasing said tongue against said periphery of said disk and for biasing said toggle overcenter in one direction, said disk including a recess in the periphery thereof, a ratchet, a pawl mounted on said operating arm and engaging said ratchet for advancing said ratchet each time said operating arm is moved between stopping and starting positions, gear

means between said ratchet and said disk for effecting rotation of said disk upon movement of said ratchet, means dependent upon a predetermined number of actuations of said ratchet for positioning said recess in alignment with said gear to afford movement of said toggle member to said first position, and a pivoted trip arm for engaging said toggle member at a predetermined abnormally high maximum temperature when said toggle member is in said first position for breaking said toggle member to terminate opposition by said toggle member to movement of said arm.

11. A refrigerator control comprising a pivoted two-part operating arm including a first part and a second part, an overcenter spring between said parts for effecting relative snap action movement of said parts for starting and stopping refrigeration at predetermined maximum and minimum temperatures, a temperature-responsive element for effecting movement of said first part of said arm, a first biasing spring engaging said first part of said arm for opposing said temperature-responsive element, means for adjusting said spring to vary said maximum and minimum temperatures, a stop for engaging said first part of said operating arm to limit movement of said first part in a refrigeration-starting direction, a toggle member movable between a first position wherein said toggle member acts as a stop for blocking movement of said arm to its refrigeration-starting position and a second position wherein said toggle member does not obstruct movement of said arm, a cam engaging said toggle member for affording movement of said toggle member between said first and second positions, means actuated at a predetermined abnormally high maximum temperature when said toggle member is in said first position for breaking said toggle member to terminate opposition by said toggle member to movement of said arm, a second spring for opposing movement of said temperature-responsive element when said toggle member is in said first position, and means for

adjusting said second spring to vary said abnormally high maximum temperature independently of the variations in maximum and minimum temperatures effected by adjustment of said first spring.

12. A refrigerator control comprising a pivoted operating arm movable between two positions for starting and stopping refrigeration at predetermined maximum and minimum temperatures, a temperature-responsive element for effecting movement of said arm, a biasing spring engaging said arm for opposing said element, a toggle member movable between a first position wherein said toggle member acts as a stop for said arm and a second position wherein said toggle member does not obstruct movement of said arm, said toggle member including two pivoted elements, a cam, a spring for biasing one of said pivoted elements against said cam and for biasing said toggle member overcenter in one direction, the other of said pivoted elements including a portion engaging said one of said pivoted elements to limit the amount of overcenter movement of said toggle members in said one direction, said cam affording movement of said toggle member between said first position and second position, and a pivoted trip arm for engaging said other of said pivoted elements of said toggle member to shift said toggle member overcenter in the opposite direction for terminating opposition by said toggle member to movement of said arm.

CHARLES S. GRIMSHAW.
